UNITED STATES PATENT OFFICE.

JAMES MONROE HALL, OF SULPHUR SPRINGS, TEXAS.

LAMP-SOCKET.

1,017,051.

Specification of Letters Patent. Patented Feb. 13, 1912.

Application filed August 14, 1911. Serial No. 643,876.

To all whom it may concern:

Be it known that I, JAMES M. HALL, a citizen of the United States, residing at Sulphur Springs, in the county of Hopkins 5 and State of Texas, have invented certain new and useful Improvements in Lamp-Sockets, of which the following is a specification, reference being had to the accompanying drawings.

10 My invention relates to new and useful improvements in devices classed under the head of illumination and more particularly to an electric lamp socket, the primary object of the invention being to provide a device of this character having means thereon for the regulation of the intensity of the current passing therethrough.

15 A further object of the invention resides in the provision of a lamp socket having a resistance coil therein with which the line wires are adapted to coöperate, and a further object resides in providing a plurality of contact posts to which the wires of the resistance coil extend.

20 Still another object resides in the provision of a manually operated slide adapted to contact individually with said contact posts.

25 A still further object resides in the provision of a metallic shell through which the slide operates and which forms a current conductor which forms part of the circuit between the two line wires.

30 A still further object resides in providing a device which is comparatively simple in construction, thereby readily and cheaply manufactured, and one which is very effective and useful in operation.

35 With these and other objects in view, my invention consists in the novel features of construction, combination and arrangement of parts as will be hereinafter referred to and more particularly pointed out in the specification and claims.

40 In the accompanying drawings forming a part of this application, Figure 1 is a side elevation of the device set up for operation.

45 Fig. 2 is a longitudinal section therethrough as seen on the line 2—2, Fig. 1. Fig. 3 is a side elevation of the device with the shell and outer casing removed. Fig. 4 is a transverse section as seen on line 4—4, Fig. 1, Fig. 5 is a diagrammatic view showing the circuits, and Fig. 6 is a detail perspective view of the slide member which is used 50 to complete the circuit.

In carrying out my invention, I shall refer to the drawings in which similar reference characters designate corresponding parts throughout the several views and in which 1 and 2 indicate, respectively, upper and lower heads, said heads being formed of wood, rubber or any other nonconducting material, and the lower head 2 being of greater diameter than the upper. Extending through said heads 1 and 2 and retaining the same in spaced alinement one above the other, is a central tubular member 3, said tubular member leading at its upper end to a cap 4 mounted on the upper head 1, while the lower end thereof leads to a cavity 5 in the lower or outer face of the head 2. Extending through said tubular member 3 at its upper end through the cap 4, is a pair of line wires 6 and 7, said line wire 6 extending the complete length of said tube and leading to a contact point 8 in the upper or inner wall of the cavity 5 of said lower head 2. This cavity 5 in the lower face of the head 2 is circular, and mounted therein, is a threaded sleeve or the like 9 which is adapted to receive the threaded portion 10 of the usual or any preferred form of electric bulb 11. When properly seated in said socket, the contact point 12 of the bulb is adapted to contact with the terminal 8 of the line wire 6. The other contact point 13 of the bulb is adapted to engage a terminal 14 in one side of the sleeve 9 which is received therein from one end of a wire 15 which extends through a slot 16 in the head 2. This slot extends from the cavity to the outer periphery of the head, and the wire 15 has an outer terminal 17 mounted in the outer periphery of said head beyond the slot 16, the purpose of which will be hereinafter and more particularly described. At this point, it must be stated that a metallic cylindrical shell 18 is also provided, the lower end of which is adapted to be secured to the lower head 2 by means of the screws 19, one of which is entered through the slot 16 of said head, while the upper end thereof is bent inwardly somewhat to form a neck 20 to engage the upper portion of the upper head 1, it being understood that said upper head is of smaller diameter than said lower head. The neck 20 is secured to said upper head by means of screws 21, and it will be appreciated that in view of the fact that one of the screws 19 enters the slot 16 to contact with the wire 15 extending therethrough,

the current passing therethrough will be conducted through said metal shell 18.

As before stated, the line wire 7 enters the tube 3 at the upper end thereof with the wire 6, but the same does not extend completely therethrough, as does said wire 6, but extends through a radial slot 22 in said head 1 to be engaged with the first of a series of contact posts 23 arranged in spaced alinement on the outer periphery of said head 1. As shown in the drawings, there are five of these contact posts 23, but it will be readily understood that any number desired may be provided and that this number is merely used as a matter of convenience, and leading from the first of said posts, is an additional insulated wire 24 which is wound the full length of the central tube 3 and returned in a like manner to be engaged with the second of the posts 23. Extending from this second post is another insulated wire 25 which is wrapped in a similar manner over the wire 24 and returned to the third post, while a further wire 26 leads from said third post and is wrapped in a similar manner about the wire 25 and returns to the fourth post of the series 23, and a still further wire 27 extends from said fourth post and is wrapped in a like manner about the other wires to be returned and engaged with the last post in the series. As shown, these wires 24, 25, 26 and 27 are coiled, but it will be readily understood that any desired wire may be used, the coil wire being the most preferable, however, in view of the resistance that the same affords. As stated, this series of contact posts 23 is disposed on the outer periphery of the upper head 1, but as the neck 20 of the metal shell 18 is so disposed as to engage the upper edge of said head 1, said shell will have no portion thereof in engagement with said posts. I have, therefore, provided means whereby the current which passes through said shell from the wire 15 may be conducted to any of the posts 23, thereby completing the circuit. To this extent, I provide the upper portion of the shell 18 with a guide member 28 which is mounted on the outer face thereof and forms a slide-way for the slide member 29. This slide member has a laterally extending arm 30 thereon which extends through a slot in said guide member 28 so that the movement of said slide member may be limited, and the arm 30 is provided with a finger piece or handle member 31, whereby the same may be readily moved when desired. The metallic shell 18 is also provided in alinement with the guide member 28, with an elongated peripheral slot 32 which, when the shell is properly positioned on the heads 1 and 2, is disposed immediately over the series of contact posts 23, and the slide member 29 is provided with an elongated spring tongue 33 which extends through

said slot 32 and is adapted to contact with the posts 23 as said slide is moved in its guide-way. This slide being of metal, is adapted to conduct the current passing through said shell 18 to the various posts and when engaged with the first of the series of posts, will conduct the current direct from said posts through the wire 7, while when engaged with the last of the series of posts, the current necessarily must pass through the series of wires 24, 25 26 and 27, which offer considerable resistance. The result, therefore, will be that when said slide is positioned so that the tongue 33 thereof is engaged with the first of the series of posts, the intensity of the current will be at its greatest, thereby offering a very bright light, while as the slide is moved so that said spring tongue engages the other contact post, the intensity of the current will be reduced, due to the resistance, until the last post is reached, whereupon there will be but a very small amount of current passing through the device. As stated, the slide is provided with a slot through which the arm 30 extends, and when said arm is at one extremity of the slot, the spring tongue 33 will be disposed in engagement with the first of the series of posts, while when disposed at the other extremity, the spring tongue will be out of engagement with all of the same, thereby breaking the current entirely.

In order to provide a neat operating device and also to prevent any possible chance of obtaining a shock from the current which is passing through the device, I provide an outer casing or covering 34 which is formed of rubber or any other preferred non-conducting material.

In practice, my improved socket may be made any desired size, it being understood that the same, as disclosed in the drawings, is somewhat enlarged, and in any instance, the cavity in the lower head of the device having the threaded sleeve therein, is made of a standard size, so that the same may readily receive a bulb of the standard size. This device may be dropped as the ordinary socket, from a ceiling or wall or may be mounted therein, as desired, as the mounting thereof will have no effect, whatsoever, upon the operation of the same, and when a bulb is placed in the cavity in the lower head, it will be seen that the two contact points 12 and 13 thereof will, respectively, contact with the points 8 and 14 of the socket. The current, under these conditions, is brought on the one hand, to the series of contact posts 23, and on the other hand, is brought up through the metallic shell 18 to the slide 29, whereby when said slide is moved so that the spring tongue 33 contacts with any of the posts 23, the circuit will be completed and an illumina-

tion will occur in the bulb. The arrangement of these contact posts with respect to the wire 7, which conducts the current through the slot in the head 1 to the post 5 23, is entirely optional, and for convenience, I have referred to the first contact post of the series as being that one which is nearest the slot 22. The slide 29, therefore, in its 10 normal position, will be at the left of the slot 32, that is, out of the contact with the posts and when moved a slight distance to the right so that the spring tongue 33 of said slide engages the last or end contact post, the circuit will be immediately completed 15 and a dim light be caused in the bulb.

When it is desired to increase the intensity of the current passing through the device, the slide is moved farther to the right, and at each successive post, the intensity 20 of the current will be increased, due to the lessening of the resistance of the circuit so that when the first or opposite end post is reached, the brightest light will be obtained.

From the foregoing, it will be seen that I 25 have provided an improved electric lamp socket wherein means is provided for the regulation of the intensity of the current which is adapted to pass therethrough, whereby the illumination resulting therefrom may be adjusted. It will further be seen that in the accomplishment of this result, resistance coils are formed within the socket which coöperate with the line wires. It will further be seen that I have 30 provided a plurality of contact posts to which said resistance coils extend.

It will further be seen that I have provided a slide on the socket, said slide having an extension thereon, which is adapted to 40 contact with said series of contact posts, whereby the intensity of the current may be decreased or increased accordingly.

It will further be seen that I have provided a metallic shell which forms a current conductor and upon which the slide 45 is mounted, thereby conducting the current of said shell to the contact posts and forming, in itself, a contact maker and breaker.

It will still further be seen that my device 50 is extremely simple and durable in construction, whereby the same may be readily and cheaply manufactured, and one which is very effective and useful in operation.

55 While I have particularly described the various features of the preferred form of my invention, it will be understood that various changes in form, proportion and in the minor details of construction may be 60 resorted to without departing from the spirit of the invention.

What I claim is:—

1. In a device of the class described, the combination with a bulb; of a socket therefor, comprising a metallic cylindrical mem-

ber, insulated heads for said member, line wires extending through said heads, one of which has a terminal in one of said heads, while the other has a terminal in the other head, a plurality of coils within said cylindrical member having terminals mounted on one of said heads and in connection with one of said line wires, means on the other head to receive said bulb, and additional means to complete the circuit from said bulb to the 70 terminals of said coils, a portion of said last referred to means being adjustable to regulate the intensity of the current therethrough.

2. A device of the class described, comprising the combination with a bulb; of a socket therefor, comprising a metallic cylindrical member, insulated heads therefor, one of said heads being provided with a cavity for the reception of said bulb, line wires entering one of the heads of said cylindrical member, one of said wires continuing to the opposite head to form a terminal in the cavity thereof, the other line wire extending laterally through the other head and forming 80 a terminal on the periphery thereof, said last referred to terminal being spaced from the metallic cylindrical member, a plurality of coils within said cylindrical member having terminals on the last referred to head and connected with the terminal of the last referred to line wire, an additional wire extending from the cavity in the opposite head to said cylindrical member, and a slide carried by said cylindrical member adapted to 85 engage a plurality of contacts formed from said coils to complete the circuit and regulate the intensity of the current passing therethrough.

3. In a device of the class described, the combination with a bulb; of a socket therefor, comprising a metallic cylindrical member having a slot in the periphery adjacent one end thereof, insulated heads therefor, line wires extending through said heads, one of which has a terminal in the one head, while the other has a terminal in the other of said heads, a plurality of coils within the cylindrical member having terminals mounted on one of said heads in connection with the terminal of the line wire therein, means on the other head to receive a bulb, a slide, guiding means on said cylindrical member for said slide, said slide being provided with a spring tongue disposed through the slot in said cylindrical member and adapted to contact with the terminals of said coils and the terminal of the line wire, and a finger piece on said slide, whereby the same may be manually operated.

4. A device of the class described, comprising the combination with a bulb; of a socket therefor, comprising a metallic cylindrical member provided with a peripheral slot adjacent the upper end thereof, insu-

lated heads for said cylindrical member, one of which is provided with a cavity for the reception of said bulb, line wires extending through one of said heads, one of said line wires having a terminal in said mentioned head, the other of said line wires extending through the cylindrical member and having a terminal in the cavity of the other head, a plurality of coils within said cylindrical member having terminals on the first mentioned head in alignment with the terminal of the line wire thereon, an additional wire having terminals, respectively, in the wall of said cavity and said cylindrical member and means to complete the circuit between said line wires, comprising a slide mounted

on the periphery of said cylindrical member adjacent the upper end thereof, said slide being provided with a spring tongue at one end thereof extending through the slide in said cylindrical member, said spring tongue being adapted to contact with the terminals of the coils and line wire on the adjacent head, a finger piece on the slide for manual operation thereof, and means to limit the movement of said slide.

In testimony whereof I hereunto affix my signature in the presence of two witnesses.

JAMES MONROE HALL.
